ARMCHAIR

Vittorio Introini, Gallarate, Italy, assignor to Proposals
S.r.L., via Postporta, Gallarate, Varese, Italy

Filed Dec. 21, 1970, Ser. No. 26,604

Term of patent 14 years

Int. Cl. D6—02

U.S. Cl. D6—69

FIG. 1 is a front-elevational view of the armchair embodying my new design;

FIG. 2 is a side-elevational view of the same armchair; and

FIG. 3 is a rear-elevational view thereof.

I claim:

The ornamental design for an armchair, as shown.
